RAZOR

Filed Aug. 30, 1927

FIG. 2

Inventor
Dean J. Case

By Clarence Walker

His Attorney

UNITED STATES PATENT OFFICE

DEAN J. CASE, OF LITTLE VALLEY, NEW YORK

RAZOR

Application filed August 30, 1927. Serial No. 216,478.

This invention relates to an improvement in razors and more particularly to a razor and guard therefor.

An object of this invention is to provide 5 a straight edge or barber's razor and guard therefor which eliminates the usual danger to the operator of cutting himself.

Another object of this invention is to provide a straight edge razor with an adjustable guard which guard automatically prevents the operator from injuring himself 10 while shaving.

A further object of this invention is to provide a razor of the straight edge type, 15 and an automatically adjusted guard therefor which does not interfere with stropping or honing the blade nor in any way with the normal use thereof.

Other objects of this invention will appear 20 from a consideration of the following specification taken in connection with the accompanying drawings and in which

Fig. 1 is a side elevation of this invention and illustrates the position of the 25 guard with relation to the cutting edge of the razor;

Fig. 2 is a view taken on the line 2—2 of Fig. 1 and illustrates the limit of swing 30 of the guard with relation to the blade of the razor;

Fig. 3 is an enlarged fragmentary view 35 showing the manner of pivotally positioning and retaining the inner end of the guard with relation to the shank of the blade; and

Fig. 4 is an enlarged fragmentary view 40 illustrating the manner of securing the outer end of the guard with relation to the blade.

Referring to the drawing and more particularly to Fig. 1, this invention comprises 45 a handle portion 10, a blade 11 and guard 12. The blade 11 is pivotally secured at 13 to the handle portion 10 in the usual manner for razors of this type. The guard 12, at its upturned inner end 15, is secured 50 to the shank portion 14 of the blade 11 and at its upturned outer end 16 is pivotally secured to the back portion 18 of the blade 11. The cutting or shaving edge 20 of the

blade 11 is the usual shape and the guard 12 is adapted to follow the absolute contour of the cutting edge 20 in a manner and for a purpose about to be described.

The guard 12 may be made from any 55 suitable metal rod but preferably is made of tempered steel in order to insure proper rigidity and alignment with the cutting edge 20 at all times. The portion 21 of the guard is parallel to the edge 20 of the 60 blade 11 and spaced therefrom a sufficient distance to permit contact with the face or strop. As previously stated the guard 12 terminates in ends 15 and 16 which ends 65 are pivotally secured to the blade 11 thereby permitting the guard to move from one side to the other of the cutting edge 20.

In back of the cutting edge 20 and into the under face of the shank 14 an opening 22 is drilled. This opening 22 is slightly 70 larger than the inner end 15 of the guard 12 which is placed therein and is secured to the shank 14 by means of a pin or screw. The pin 23 passes through the shank and the end 15 of the guard thereby retaining 75 said end within the opening 22. The opening in the end of the portion 15, in which the pin 23 is positioned, being somewhat larger than the diameter of the pin permits said portion to swing to either side within 80 the predetermined limit of the opening 22.

In the outer end of the back portion 18 of the blade 11 an opening 24 is provided which receives an inwardly projecting tip portion 25 of the end 16 of the guard. 85 Substantially midway between the tip portion 25 and the portion 21 on the end 16 is provided a stop 26. The stop 26 may be formed from the guard itself, or may be as is shown in the drawing, a small 90 channeled member secured to the end 16 in any desirable manner. The stop 26 is channeled at 27 to provide sufficient space 95 for the end of the cutting edge 20 to fit therein.

In as much as the inner end 15 of the guard 12 is pivotally secured to the blade 11 and the outer end 16 is likewise pivotally secured to said blade the guard 12 is free 100 to be moved sidewise in either direction past

the cutting edge 20 by any slight pressure against it. The limit of movement of the guard 12 in either direction is partially determined by the stop 26 located at the outer end of the guard and also by the size of the opening 22 in the shank 14 with relation to the end 15 of the guard. The movement of the guard 12 is very slight and in fact only just enough in either direction 10 past the center of the cutting edge 20 to permit said edge to merely scrape the surface it comes in contact with but not to cut or bite into said surface.

It is obvious that if the guard 12 swings 15 sufficiently to either side of the cutting edge 20 to permit said edge engagement with a surface there will be sufficient clearance of the guard to facilitate stropping or honing without removing said guard from the blade.

20 Attention is called to the fact that the guard is free to swing to either side of the cutting edge (within a predetermined space) without manual adjustment of any kind. In other words, the razor may be used in 25 the right hand and immediately transferred to the left without any adjustment, the pressure against any surface acting to instantly adjust the guard to the other side of the cutting edge.

30 Since the guard 12 permits only a proper use of the cutting edge 20 there can be no danger of cutting to the operator regardless of whether he be inexperienced or use the razor improperly. Furthermore it has 35 always been difficult to handle and care for razors of this type in such a manner as to prevent them being nicked. The position of the guard protects the cutting edge at all times from coming in contact with foreign 40 articles and thereby largely eliminates the possibility of ruining the cutting edge.

While only one modification of this invention has been shown and described, applicant does not intend to be limited thereto 45 since it is obvious that other modifications or adaptations may be made without departing from the spirit and scope of this invention as set forth in the following claims.

Having thus set forth my invention, what 50 I claim is new and for which I desire protection by Letters Patent is:

1. A barber's razor comprising a handle, a blade having a shank pivotally mounted upon said handle, a rod-like guard spaced 55 from and shaped to conform to the contour of said blade being terminated in upturned ends, said shank having a vertical pocket therein by which to receive the inner end of said guard, a pin loosely securing said 60 guard within said pocket, the outer end of said blade having an opening therein by which to pivotally engage the outer end of said guard, a channular stop formed upon the outer upturned end of said guard and 65 adapted to engage the outer end of said

blade to limit the relative movement between said blade and said guard.

2. A barber's razor comprising a handle, a blade having a shank pivotally joined upon said handle, a rod-like guard spaced 70 from and shaped to conform to the contour of said blade, said guard terminating in upturned ends, said shank having a vertical pocket formed in the under face thereof, the inner end of said guard being mounted within said pocket, means loosely securing 75 the inner end of said guard within said pocket, the outer end of said blade having an opening therein by which to pivotally engage the outer end of said guard, a channular stop formed upon said outer end whereby to limit the relative movement of 80 said blade and said guard.

3. A barber's razor comprising a handle, a blade having a shank pivotally joined upon said handle, a rod-like guard spaced 85 from and shaped to conform to the contour of said blade, said guard terminating in upturned ends, said shank having a vertical pocket formed in the under face thereof, the inner end of said guard being mounted 90 within said pocket, means loosely securing the inner end of said guard within said pocket, said securing means being transversely disposed with relation to the direction of pivotal movement of said guard, the outer end of said blade having an opening 95 therein by which to pivotally engage the outer end of said guard, a channular stop formed upon said outer end whereby to limit 100 the relative movement of said blade and said guard.

In testimony whereof I have affixed my signature.

DEAN J. CASE.
